UNITED STATES PATENT OFFICE

CHARLES A. MOORE, OF EDINA, MINNESOTA

MEANS FOR CONDITIONING AND CIRCULATING THE AIR IN COLD STORAGE ROOMS

Application filed February 7, 1929. Serial No. 338,181.

My invention relates to improvements in means for circulating and conditioning the air in cold storage rooms.

A prior application for patent, Ser. No. 5 334,511 heretofore filed by myself discloses means for refrigerating and controlling the circulation of air in a cold storage room, the same including banks of overhead refrigerant coils extending longitudinally of the room 10 over a central trucking aisle, said banks of coils being spaced apart horizontally to form a central port in the coil assembly. About this assembly are side and end baffle walls, the upper edges thereof, like the uppermost 15 reaches of the coils in said assembly, being disposed beneath the ceiling of the room to provide a space between the coils and ceiling into which the air along the ceiling may flow. Located in this space in a vertical plane, 20 medially of said port, is a longitudinal ceiling baffle consisting of superimposed refrigerant pipes adapted to be frosted together. Taking off from the feed pipe of this longitudinal ceiling baffle and returning to the 25 return pipe of said baffle are a number of valved refrigerant pipes forming lateral baffles, the same being located at intervals between the ends of the room. The longitudinal baffle marks off two main bays in the 30 room, while the lateral baffles mark off smaller bays in each main bay. Directly beneath each lateral baffle is a conduit open at the upper side thereof, its outer end being closed and its inner end open and projecting into the 35 space occupied by the refrigerant coils between the side wall baffles. The circulation of air in the room is mainly confined to two circuits as follows: Air about the coils, being 40 refrigerated, descends at the central aisle, thence divides and flows in opposite directions toward the side walls of the room, thence rises along the relatively warm walls to the upper portion of the room, thence flows inward from the sides along the ceiling of the 45 room into the space above the refrigerant coils and thence descends again, thus completing the cycle. The longitudinal baffles prevent the relatively warm air of a relatively 50 high percentage of humidity at the ceiling from crossing over the refrigerant coils from 55 one side of the room, where newly stored 60 lading of relatively high temperature may be placed, to the other side of the room where refrigerated goods may be located. And the lateral baffles likewise prevent the passage of 65 relatively warm air of a relatively high percentage of humidity from position at the ceiling above a newly deposited load of goods of relatively high temperature in a direction 70 longitudinally of the room into an adjacent 75 bay which may be occupied by goods of relatively low temperature. In addition to physically blocking the flow of air at the ceiling of the room between adjacent bays marked off by the lateral baffles, said lateral baffles, in 80 refrigerating the air adjacent thereto, cause the descent of such air, the same being received in the conduits therebeneath and directed thereby into the space between the side baffle walls, wherein, as previously noted, the 85 refrigerant coils are located. From the foregoing, it will be understood that in the invention disclosed in said prior application, Ser. No. 334,511, there is a natural convective and diffused circulation of air, induced by 90 gravity, in the particular circuits noted.

An object of the present invention is to associate with a structure, embodying the features aforesaid, such means as will stimulate such natural, convective and diffused circulation of air in a cold storage room and enhance the refrigerating effect of the equipment provided, it being a purpose of the present invention to take advantage of the various elements in their respective relations 95 in the prior combination to produce the results of the instant invention in a simple and effective manner.

With the foregoing and other objects in view, which will appear in the following description, the invention resides in the novel combination and arrangement of parts and in the details of constructions hereinafter described and claimed.

In the drawings, Fig. 1 is a view showing, in section, the walls of a cold storage room and illustrating, in plan, an embodiment of my invention in air circulating and conditioning means arranged within the room; Fig. 2 is a vertical sectional view taken as on 100

the line 2—2 of Fig. 1 and Fig. 3 is a similar view taken as on the line 3—3 of Fig. 1.

In the drawings, I have illustrated a room A having side walls 10, end walls 11 and ceiling 12, said room being elongated in accordance with the presently accepted designs of rooms for commercial cold storage plants, wherein a central trucking aisle is provided in a room for the transfer of lading to and from the storage spaces along the length of the room at either side of the central aisle.

Located overhead along this central aisle is the major portion of the apparatus embodying my invention, the remaining portions being represented in lateral baffles and conduits therebeneath, as will more fully hereinafter appear.

In the part of the structure extending overhead along the central trucking aisle, I supply a U-shaped assembly of refrigerant conducting pipes 13, the two legs of the assembly comprising horizontally spaced banks B extending lengthwise of the aisle and the base comprising a connecting bank C extending transversely of the aisle at one end of the pipe assembly. Each of said banks of pipes consists of three horizontally spaced tiers, the corresponding pipe portions in the different tiers of said banks being parts of a length of pipe bent in U-shaped formation. At the open end of the pipe assembly, opposite the connecting bank C, are two upright refrigerant headers 14 and 15, the former being a feed header, which is connected at its lower end with a feed main 16, and the latter being a return header, which is connected at its upper end with a return main 17. These mains 16 and 17 are connected with a source of refrigerant supply, not shown. Each of the U-shaped pipes 13 is connected at one end thereof with the feed header 14 and at its other end with the return header 15. And each pipe 13 is fitted with a valve 18 near its connection with said feeder header 14, a second valve 18 being also fitted therein near the connection between the pipe and said return header 15. The pipes 13 are each supported from the ceiling 12 by means of hanger straps 19 supplied with hooks 20 in which the reaches of pipe rest. The distance between the reaches of the pipes 13 in each tier, particularly the outer tiers, is such that the accumulation of frozen condensation on said pipes will cause the frosting together of the same in solid formation. And the distance between the ceiling 12 and the uppermost reaches of pipe in the pipe assembly is such as to provide an air space D (Fig. 2) between said assembly and ceiling. Suspended from the ceiling 12 by means of hanger straps 21 and surrounding the assembly of refrigerant pipes 13 are side baffle walls 22 and 23 and end baffle walls 24 and 25, the upper edges of said baffle walls being disposed slightly beneath the level of the upper reaches of the

pipes 13 and, consequently, being clear of the air space D above the assembly of pipes 13. The side baffle walls 22 and 23 and the end baffle wall 24 are spaced from the corresponding sides and end of the pipe assembly to provide communicating side and end passageways E, F and G. Between the end baffle wall 25 and the adjacent end of the pipe assembly is a partition wall 26, which together with said end baffle wall 25 forms an air header H, the same being in communication with said side passageways E and F. In this connection, it will be noted that the communicating passageways E, F and G are open along the top thereof. Said passageways, however, may be closed at the bottom by allowing sufficient frost to accumulate on the reaches of the lowermost pipe 13, whereby the spaces between baffle walls and pipe are blocked, Figs. 2 and 3. The air header H is also open along the top thereof, but obviously may be closed, if and when desired, by any suitable closure.

The partition wall 26 is formed with an opening 27 therein receiving the blades of a fan 28 which is supported upon a bracket 29 secured to the inner side of the end baffle wall 25. This opening 27 and the fan 28 have a common axis lying in a vertical plane medially of port I formed between the banks B of pipes 13, the position of said axis in elevation being between the horizontal planes of the uppermost and the lowermost of the refrigerant pipes 13. At the lower edges of the baffle walls 22, 23, 24 and 25 are inwardly extending drain members 30 forming a continuous gutter from which accumulated condensation is drained as by means of a drain pipe 31. In this connection it may be noted that the drain member 30 at the lower edge of the end baffle wall 25 closes the bottom of the air space in the header H, which, as previously stated is formed between said end baffle wall 25 and the adjacent partition wall 26.

Extending along the ceiling 12, medially of the port I is a longitudinal ceiling baffle J consisting of upper and lower reaches of a refrigerant pipe 32 formed with a hair pin bend at 33. Said reaches of the pipe 32 are closely adjacent each other and adapted to be frosted over solidly by the accumulation thereon of frozen condensation, the upper reach of said pipe being disposed closely adjacent to the ceiling 12. The lower reach of the refrigerant pipe 32 communicates through a connection 34 with the feed header 14, said connection being fitted with a valve 35. And the upper reach of said pipe 32 communicates through a connection 36 with the return header 15, said connection 36 being fitted with a valve 37. Lateral ceiling baffles K, similar in construction to the longitudinal baffle J are provided at intervals between the ends of the room, each of said baffles comprising a refrigerant pipe 38, bent as at 39, the upper and lower reaches

thereof being respectively connected with the upper and lower reaches of the pipe 32 forming the longitudinal baffle J, the lower reach being fitted with a valve 39. These lateral ceiling baffles K, extending from the structure over the central trucking aisle in the room, reach substantially to the side walls 10. Beneath each lateral baffle K is a trough or conduit 40, opening along the top thereof directly below the baffle, said trough having a closure 41 at its outer end, but being open at the inner end thereof. Said inner end of each trough or conduit 40 is fitted in a notch cut in the upper margin of one of the side wall baffles 22, 23 and communicates with the space between said side baffle walls in which the assembly of pipes 13 is disposed. Hangers 42, 43 and 44 support the pipes 32, 38 and the troughs 40, respectively.

As previously indicated, the circulation set up in a room equipped with a structure of the instant nature is confined generally to two circuits as follows: The air about the banks B of the pipes 13 and in the port I between said banks being refrigerated descends by gravity in the central aisle dividing at the center of the room and flowing toward the side walls, mainly at the lower portions of the lading spaces at either side of the aisle. Rising along the relatively warm side walls, the air ascends to the ceiling, thence flows inward from either side passing along the ceiling and into the space D above the pipes 13, and thence again descends about the pipes 13 and port I, thus completing the cycle. Warm air of relatively high humidity which has ascended to the ceiling from a pile of relatively warm lading is kept from passing through the space D above the pipes 13 and descending on refrigerated goods at the opposite side of the aisle by means of the longitudinal baffle J. And, similarly, by means of the lateral baffles K such warm air is kept from passing along the ceiling, longitudinally of the room, to another bay at the same side of the aisle and descending in said bay on refrigerated goods therein disposed. The air refrigerated about the longitudinal baffle J descends through the port I between the banks B of pipes 13, while the air refrigerated about the lateral baffles K descends into the troughs or conduits 40 and thence flows therethrough into the space between the side baffle walls 22 and 23, where it is further refrigerated by the pipes 13 and caused to descend in the main, central stream medially of the room.

The application of my present invention to a structure functioning, as above pointed out, stimulates the flow of the air in the circuits established by gravity and renders the refrigerating equipment more effective. Thus, I permit the outer tiers of pipes 13 to become frosted over as indicated in dotted lines in Figs. 2 and 3. This seals the inner walls and the bottoms of the passageways E, F and G.

With the fan 28 in operation, the air flowing along the conduits 40 passes into the passageways E, F. Also, a part of the air flowing along the ceiling and into the space D over the pipe assembly passes into said passageways E, F, and also into the passageway G and the open upper part of the air header H. This air in these passageways is drawn along the same to the fan 28 and thence blown by the fan into the port I. In passing through said passageways E, F and G, the air is cooled by the pipes 13 in the outer tiers and is further cooled by the inner tiers of said pipes after leaving the fan and upon entering the port I. When the refrigerating and air circulating effect by gravity alone suffices, the operation of the fan 18 is discontinued and the outer tiers of pipe defrosted, partially at least.

The valves 18, 35 and 39 provide for selectively bringing into and putting out of operation, the pipes 13 and ceiling baffles J and K, respectively.

Changes in the specific form of my invention, as herein disclosed, may be made within the scope of what is claimed without departing from the spirit of my invention.

Having described my invention, what I claim as new and desire to protect by Letters Patent is:

1. The combination with a room of overhead refrigerating and air circulating means extending longitudinally of the room between the side walls thereof, said means including refrigerant pipes arranged in tiers spaced apart horizontally to form a port between them, side and baffle walls about the tiers of pipes, the upper edges of said baffle walls and the upper refrigerant pipes being disposed below the ceiling to provide a space for the passage of air between the same and the ceiling, each side baffle wall being spaced horizontally from the adjacent tier of pipes to form a passageway open at the top and extending longitudinally of the room between said end baffle walls, the adjacent pipes in each tier being close to each other and adapted to be frosted together solidly, the accumulation of frost on lower pipe of each tier being adapted to close the bottom of the passageway formed by the tier and the adjacent side baffle wall, refrigerating elements extending laterally of the room and forming baffles at the ceiling thereof, air conduits, one for each of said refrigerating elements, each conduit opening at its upper side beneath its respective refrigerating element and opening at its inner end into one of said passageways, a partition wall adjacent one of the end baffle walls forming, in connection therewith, an air header communicating with said longitudinal passageways, said partition wall having an opening therein registering with the port between said tiers of refrigerant pipes, a fan arranged to draw the air from said air

header and blow it through said opening into and along the port between said tiers of pipe.

2. The combination with a room of overhead refrigerating and air circulating means extending longitudinally of the room between the side walls thereof, said means including refrigerant pipes arranged in tiers spaced apart horizontally to form a port between them, side and end baffle walls about the tiers of pipes, the upper edges of said baffle walls and the upper refrigerant pipes being disposed below the ceiling to provide a space for the passage of air between the same and the ceiling, each side baffle wall being spaced horizontally from the adjacent tier of pipes to form a passageway open at the top and extending longitudinally of the room between said end baffle walls, the adjacent pipes in each tier being close to each other and adapted to be frosted together solidly, the accumulation of frost on lower pipe of each tier being adapted to close the bottom of the passageway formed by the tier and the adjacent side baffle wall, a partition wall adjacent one of the end baffle walls forming, in connection therewith, an air header communicating with said passageways, said partition wall having an opening therein registering with the port between said tiers of refrigerant pipes, and a fan arranged to draw the air from said air header and blow it through said opening into and along the port between said tiers of pipe.

3. The combination with a room of overhead refrigerating and air circulating means extending longitudinally of the room between the side walls thereof, said means including banks of refrigerant conductors spaced from the ceiling to provide an air space thereover and spaced horizontally from each other to provide a port communicating with said air space, side baffle walls, one adjacent each bank of refrigerant conductors, each side baffle wall and its respective bank of refrigerant conductors forming an air passageway open at the top thereof, spaced walls at one end of the conductor assembly forming an air header communicating with said longitudinal passageways, the inner wall of said two spaced walls having an opening therein registering with the port between said banks of refrigerant conductors, and a fan arranged to draw the air from said air header and blow it through said opening into and along said port.

4. The combination with a room of overhead refrigerating and air circulating means extending longitudinally of the room between the side walls thereof, said means including banks of refrigerant conductors spaced apart horizontally to provide a port between them, side baffle walls, one adjacent each bank of refrigerant conductors, each side baffle wall and its respective bank of refrigerant conductors forming an air passageway open at the top thereof, an air head-

er at one end of the conductor assembly communicating with said passageways, and a fan arranged to draw the air from said air header and blow it into and along said port.

5. The combination with a room of overhead refrigerating and air circulating means extending longitudinally of the room between the side walls thereof, said means including banks of refrigerant conductors spaced apart horizontally to provide a port between them, side baffle walls, one adjacent each bank of refrigerant conductors, each side baffle wall and its respective bank of refrigerant conductors forming an air passageway open at the top thereof, and means for drawing the air from said passageways and blowing it into and along said port.

6. The combination with a room of refrigerating and air circulating means extending longitudinally of the room and including a bank of refrigerant conductors, a side baffle wall adjacent said bank of refrigerant conductors forming, in connection therewith, an air passageway open at the top thereof near the ceiling, and means for drawing air from said passageway and blowing it along said bank of refrigerant conductors.

7. The combination with a room of overhead refrigerating and air circulating means extending longitudinally of the room between the side walls thereof, said means including banks of refrigerant conductors spaced apart horizontally to provide a port between them, side baffle walls, one adjacent each bank of refrigerant conductors, each side baffle wall and its respective bank of refrigerant conductors forming an air passageway open at the top thereof, refrigerating element at the ceiling of the room extending laterally thereof, means suspended beneath said refrigerating elements for receiving the air descending therefrom and conducting it into said passageways, and means for drawing the air from said passageways and blowing it into and along said port.

8. The combination with a room of overhead refrigerating and air circulating means extending longitudinally of the room between the side walls thereof, said means including a bank of refrigerant conductors, a baffle wall adjacent one side of said bank of refrigerant conductors forming in conjunction therewith an air passageway, a conduit extending laterally of the room and open along its length near the ceiling for the ingress of air thereto, said conduit leading to said passageway, and means for drawing the air from said passageway and blowing it back along said bank of conductors.

9. The combination with a room of refrigerating and air circulating means extended along the room, said means including a bank of refrigerant conductors, means forming air passageways, open at the top, along the sides

of said bank of conductors and means for drawing air from said passageways and blowing it along said conductors between said passageways.

5 10. The combination with a room of refrigerating and air circulating means extending along the room, said means including a bank of refrigerant conductors, means forming an air passageway along the side of said bank of conductors, a conduit open along the ceiling for the ingress of air thereto, said conduit leading to said air passageway, and means for drawing air from said passageway and blowing it along said bank of refrigerant conductors.

10 11. In combination, a structure forming a chamber, an assembly of banked refrigerant pipes extending along the chamber near the ceiling thereof consisting of superimposed U-shaped reaches of pipe, said assembly thus formed having a vertical central port extending along the length thereof and being closed by pipe at one end and open at the other end, headers for said pipe at the open end of the assembly, and a fan at said end thereof adapted to blow air into said port lengthwise thereof in the direction of the closed end of the assembly.

15 12. In combination, a structure forming a chamber, a bank of refrigerant conductors extending along the chamber near the ceiling centrally of said chamber and formed to provide a vertical central port extending along the same and opening through one end thereof only, and a fan at said open end of said bank arranged to blow air into said port, longitudinally thereof in the direction of the closed end.

13. In combination, a structure forming a chamber, a bank of refrigerant conductors extending along the chamber near the ceiling, and formed to provide a vertical central port extending along the same, and a fan arranged to blow air into said port longitudinally thereof from one end of the bank of conductors.

14. The combination with a room of overhead refrigerating and air circulating means centrally disposed longitudinally of the room and spaced from the ceiling thereof, said means comprising a bank of horizontally arranged refrigerant pipes spaced apart and providing a way for the descent therethrough of air from the upper to a lower portion of the room and for the passage of air lengthwise through the bank, means supplementary to said first means for refrigerating air preparatory to its endwise introduction into said bank of pipes, and means for blowing such air into the bank lengthwise thereof.

15. The combination with a room of an overhead refrigerating and air circulating assembly of refrigerant conductors extending longitudinally of the room and spaced from the ceiling thereof, said assembly being

formed for the descent therethrough from end to end thereof of air from the upper to a lower portion of the room and for the introduction of air thereto lengthwise thereof, supplementary means for refrigerating air, and means for blowing such air into said assembly in the direction of its length.

16. The combination with a room of an overhead refrigerating and air circulating assembly of refrigerant conductors extending longitudinally of the room and spaced from the ceiling thereof, said assembly being formed for the descent therethrough from end to end thereof of air from the upper to a lower portion of the room and for the introduction of air thereto lengthwise thereof, and means for blowing air into said assembly in the direction of its length.

In testimony whereof I have affixed my signature to this specification.

CHARLES A. MOORE.
